CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

RAILWAY SIGNALING SYSTEM.

1,270,806.

Specification of Letters Patent.

Patented July 2, 1918.

Application filed June 4, 1915. Serial No. 32,186.

To all whom it may concern:

Be it known that I, CHARLES LE G. FORTESCUE, a subject of the King of Great Britain, and a resident of Pittsburgh, in the county of Allegheny and State of Pennsylvania, have invented a new and useful Improvement in Railway Signaling Systems, of which the following is a specification.

My invention relates to track-circuit apparatus for railway signaling, and it has special reference to railway signaling systems which are operated by alternating currents.

My invention refers particularly to signaling systems which are employed in connection with tracks that are divided into blocks or sections of suitable lengths. The blocks are insulated from one another, and each is provided with at least one suitable 20 signaling device which is operated by means of an alternating-current motor.

One object of my invention is to provide a railway signaling system which will indicate, by any suitable means, whether or not 25 a train or car occupies a certain block of the track. Moreover, my signaling system will indicate danger to an approaching train or car when one of the rails comprising a block of the railway track is broken. According to my invention, a semaphore 30 signal, or any other suitable device, such as a signaling lamp, which may be employed to communicate the condition of the track of a railway system, will operate to indicate danger, either when a block is occupied 35 by a train or car, or when a rail comprising a block section is broken.

Railway signaling systems embodying my invention may be employed on steam railways or on electrical railways, whether operated from direct-current or alternating current circuits. Current supplied to one of the circuits comprising my signaling system is furnished from separate mains which, 45 in turn, are continuously supplied with power from a separate source of power supply. If the propulsion current utilized for the trains or cars of the railway system is furnished from alternating-current mains, it is desirable that the frequency of the propulsion current be different from the frequency of the aforementioned current supplying power to the signaling system.

In many systems now installed, it is usual 50 to operate the trains or cars of a railway

system from 25 cycle mains, and to operate the signaling devices employed in connection with the railway system from 60 cycle mains. Under these circumstances, my signaling system may be so designed that it 60 will operate when 60-cycle current only is supplied thereto, and, as a result, it will be unaffected when 25-cycle current traverses the railway system.

For a better understanding of the nature 65 of my invention, reference may be had to the following description and the accompanying drawing, in which Figure 1 is a diagrammatic view of a railway system embodying a form of my invention, and Fig. 2 is a 70 view, in elevation, of a modified form of a signaling device built in accordance with my invention.

Referring to Fig. 1, track rails 1 and 2, which comprise an insulated section or 75 block 3 of a railway system, are electrically insulated from adjoining rails 4 by means of insulating joints 5. The railway here shown is an electrical railway, the propulsion current for which is supplied from any 80 suitable source in any well known manner. In order that both of the track rails 1 and 2 may be included in the circuit of the propulsion current, I provide inductive bonds 6, adjacently disposed and on each side of 85 the insulating joints 5, to conduct the propulsion current around these joints in a usual and well known manner.

A signaling device 7, which, in this instance, is provided with a rotatable semaphore arm 8, is positioned at one end of the track section or block 3 in order to indicate to approaching trains or cars the conditions obtaining upon such track-section or block. The signaling arm 8 indicates, 90 by reason of its position, whether or not a train or car occupies the block 3, and also whether the rails 1 and 2 are in suitable condition to allow an approaching train or car to enter into said block.

The operating mechanism to vary the position of the semaphore arm 8, comprises a horizontally movable actuating arm 9 that engages a cam member 10 which, in turn, is operated by a centrifugal device 11 by 105 means of a rotatable secondary member 12 of an induction motor 13. A primary winding 14 of the induction motor 13 is connected to polyphase mains 15, shown as three-phase mains and supplied with power 110

from any suitable source, such as a three-phase alternator 16.

As mentioned above, the induction motor 13 comprises a stator having the primary winding 14 and the rotor 12 which is provided with two windings 17 and 18 so disposed thereupon as to be displaced 90 degrees from each other. The windings 17 and 18 are connected in parallel relation-
 5 ship and, through slip rings 19 and 20, to the track rails 1 and 2, respectively, of the block 3. The centrifugal device 11, which comprises pivotally mounted links 21 and elements 22 that are well known in the art
 10 and in common use in governing devices, is mounted upon the shaft 23 of the induction motor 13. One end of the governing device 11 is secured to the shaft 23 by means of a pin 24, and the other end engages a collar 25 which is slidingly mounted on the shaft 23. The position of the collar 25 is dependent upon the speed of the shaft 23 by reason of the interposed centrifugal mechanism comprising the elements 21 and 22. The
 15 actuating arm 9 of the semaphore arm 8 is operated by means of the rotatable cam member 10 which is rotated by means of engagement through an arm 26 with the aforementioned collar 25.

Under normal conditions, when no train or car occupies the block 3, the secondary member 12 of the induction motor 13 rotates at a speed considerably below synchronism, such, for instance, as one-half synchronous speed. This results from the design of the motor 13 and from the external resistance connected in circuit with the secondary windings 17 and 18 by reason of the track circuit formed by the rails 1 and 2 and the impedance bonds 6. Inasmuch as the rails 1 and 2 and the impedance bonds 6 constitute a high resistance which, in turn, is connected in circuit with the secondary windings of the induction motor 13,
 30 the speed of the secondary member is maintained considerably below synchronism. Under these circumstances, the centrifugal device 11 occupies the position shown by the dotted lines 27, and the cam member 10 occupies an upright position indicated by the dotted lines 28. Since the actuating arm 9 of the signal arm 8 tends to move toward the cam member 10 by reason of the gravity action of the arm 8, the actuating arm 9 occupies a position indicated by the dotted lines 29 and the semaphore arm 8 occupies the position indicated by the dotted lines 30. In this manner, the conditions obtaining upon the block 3, namely, that the block
 35 is open, may be communicated to an approaching train or car.

When a train 31 occupies the block 3, the rails 1 and 2 are directly connected together through the train, and a large
 40 share of the external resistance in the sec-

ondary windings 17 and 18 of the induction motor 13 is cut out of circuit. As a consequence, the rotor 12 speeds up and approaches synchronous speed. In this instance, the centrifugal device 11 and the cam member 10 occupy the positions shown by the full lines. Inasmuch as the cam 10 is turned to such position as to force the actuating arm 9 away from the centrifugal device 11, the semaphore arm 8 occupies a horizontal position, thereby indicating that the block 3 is occupied. After the train 31 withdraws from the block 3, normal conditions are restored upon the railway system, and the rotor 12 of the induction motor 13 will rotate at its normal speed. When a rail of the section 3 breaks, the secondary windings 17 and 18 of the rotor 12 are open-circuited. As is well known, the rotor 12 will cease to rotate and the centrifugal device 11 will then occupy a position indicated by the dotted lines 32, and the cam device 10 will occupy a position indicated by the dotted lines 33. When the cam device 10 occupies the position 33, the semaphore arm 8 occupies the position shown in the full lines, to indicate danger.

Since the motor 13 is designed to normally operate at substantially one-half synchronous speed, for example, 50 per cent. of synchronous speed, it will not be influenced to falsely operate the signaling device 7 when 25-cycle currents traverse its secondary windings, if the primary windings are supplied with 60-cycle currents. Inasmuch as substantially one-half synchronous speed of the motor corresponds, for all practical purposes, to the rate of vibration imparted thereto by 25-cycle currents, it will be apparent that 25-cycle currents will not affect the reliability of my signaling system, as is common in many systems heretofore installed.

In the foregoing description, I have disclosed a railway signaling system which will operate to indicate danger when either a train or a car occupies the block 3, or when either one or both of the rails 1 and 2 comprising the block 3 is broken. It may be unnecessary, however, to provide means to indicate a broken rail because of the infrequency of such an occurrence. Therefore, I may employ the arrangement shown in Fig. 2, in which the secondary windings 17 and 18 of Fig. 1 of the induction motor 13 are so designed that they will not effect rotation of the shaft 23 when connected in circuit with the rails 1 and 2 and the impedance bonds 6. In this case, the impedance of the rails and bonds is too high to permit the rotor windings to develop sufficient torque to rotate the shaft 23. In other words, the secondary member of the induction motor 13 remains stationary when normal conditions obtain upon the block 3. As a consequence

thereof, the centrifugal device 11 occupies the position shown by the full lines of Fig. 2. The slidingly mounted collar 25 operates a link mechanism 34 to maintain the semaphore arm 8 in the position indicated. When a train or car occupies the block 3, as shown in Fig. 1, the resistance of the secondary circuit of the induction motor 13 is sufficiently decreased to compel the shaft 23 to rotate at substantially synchronous speed. Under these conditions, the centrifugal mechanism 11 occupies a position indicated by the dotted lines 35. Since the collar 25 is drawn toward the motor 13 when the shaft 23 rotates, the link mechanism 34 is operated to move the semaphore arm 8 to a position indicated by the dotted lines 36. As previously explained, when the semaphore arm 8 is in the position 36, the approaching train or car is warned against advancing into the block 3.

It is to be understood that other signaling devices, such as those embodying lamp signals, may be substituted for the semaphore type of signal; that other actuating devices may be substituted for the centrifugal device 11, without departing from the spirit of my invention, and that other modifications may be made by those skilled in the art within the scope of the appended claims.

I claim as my invention:

1. In a railway signaling system, the combination with a track circuit and a signaling device, of an operating means for said signaling device comprising relatively rotatable primary and secondary members one of which has a winding connected to the track circuit and provided with resistance in its circuit that is controlled by track circuit conditions.

2. In a railway signaling system, the combination with a track circuit and a signaling device, of an operating means for said signaling device comprising an induction motor the primary member of which is supplied with polyphase alternating current energy, and the secondary member of which has a winding connected to said track circuit.

3. In a railway signaling system, the combination with a track circuit and a signaling device, of an operating means for said signaling device comprising an induction motor the primary member of which is supplied with alternating current energy, and the rotatable secondary member of which has windings displaced in phase relationship with one another and connected to said track circuit.

4. In a railway signaling system, the combination with a track circuit and a signaling device, of an operating means for said signaling device comprising an induction motor the primary member of which is supplied with alternating current energy to

generate a rotating field and the rotatable secondary member of which has windings connected in parallel to the rails constituting a block section of the railway system, the circuit resistance of said secondary windings being so adjusted that, when a train or car bridges the rails of said block section, the said member rotates at its highest speed.

5. In a railway signaling system, the combination with a track circuit and a signaling device, of an operating means for said signaling device comprising an induction motor the primary member of which is supplied with alternating currents to generate a rotating magnetic field and the rotatable secondary member of which has windings connected in parallel to the rails comprising a block section of the railway system in order that the circuit resistance of said secondary windings may have a minimum value when a train or car bridges the rails of said block section.

6. In a railway signaling system, the combination with a track circuit and a signaling device, of an operating means for said signaling device comprising an induction motor the primary member of which is supplied with alternating currents to generate a rotating field and the rotatable secondary member of which has windings connected in parallel to the rails comprising a block section of the railway system, the circuit resistance of said secondary windings being so adjusted that the secondary member will rotate normally at a speed substantially below synchronism and, when a train or car bridges the rails of said block section, the secondary member will rotate at substantially synchronous speed.

7. In a railway signaling system, the combination with track rails, bonds for connecting them to each other, and a signaling device, of an operating means for said signaling device comprising an induction motor the primary member of which is supplied with alternating currents to generate a rotating field and the rotatable secondary member of which has windings connected in parallel relationship to the track rails comprising a block section of the railway system in order that said block section may normally be connected in a closed circuit with said secondary windings.

8. In a railway signaling system, the combination with a track circuit and a signaling device, of an operating means for said signaling device comprising an induction motor the primary member of which is supplied with alternating currents to generate a rotating field and the secondary member of which has windings connected in a circuit comprising a block section of the railway system in order that the said windings may be open circuited when one of said rails is broken.

9. In a railway signaling system, the combination with a track circuit and a signaling device, of an operating means for said signaling device comprising a primary member and a rotatable secondary member in inductive relation therewith, the latter having windings connected to the track circuit and the amount of resistance connected in circuit with said secondary windings being

controlled solely by the conditions obtaining upon the track circuit, and the speed of said secondary member varying in accordance with the value of said resistance. 10

In testimony whereof, I have hereunto subscribed my name this 27th day of May, 1915.
